UNITED STATES PATENT OFFICE

JOHN STROTHER MILLER, JR., OF RAHWAY, NEW JERSEY, ASSIGNOR TO THE BARBER ASPHALT COMPANY, OF PHILADELPHIA, PENNSYLVANIA, A CORPORATION OF WEST VIRGINIA

PAVEMENT MARKING

Application filed April 2, 1927. Serial No. 180,388.

My invention relates to pavement marking and the like, and is especially adaptable and advantageous for traffic lines or other marks on roads, pavements, etc. I aim to provide 5 a simple, durable, conspicuous, and inexpensive marking, that can be easily and cheaply installed and replaced.

In the drawing, Fig. I shows my marking in place on a pavement.

10 Fig. II shows a perspective and edge view of one form of my marking.

Fig. III shows a similar view of another form of marking.

For my marking, I may employ any suitable fabric such as a textile or felted fabric: 15 e. g., cotton webbing. As shown in Fig. I, a strip 5 of such material, of suitable width, is cemented in place on the pavement 6, as by means of bituminous cement 7, such as an asphalt emulsion or other liquid asphalt of any suitable character,—or in fact by means of any suitable adhesive. The cement 7 may 20 conveniently be applied to the line or other area of pavement which the marker is to cover, and the latter then laid on and pressed down. Or, in the case of asphalt or other pavements containing bitumen at their surface, the strip 5 may be cemented in place by 25 the bitumen of the pavement itself, which 30 may be suitably softened for this purpose either by heat or by application of a suitable and sufficiently volatile solvent.

In order to prevent the cement (of whatever character) from striking through the 35 fabric strip 5 and discoloring it, I render the strip cement-proof by impregnating and/or coating it with suitable paint, varnish, lacquer, or other medium,—preferably a medium not soluble by any components of the 40 cement, nor adapted to coalesce therewith under the conditions of use. The strip 5 may be thus coated on either its upper or its lower side,—or both. When there is coating on the top side of the fabric, it may either be in 45 sufficient quantity to give a true smooth top surface, as shown in Fig. II, or only enough may be used to just cover the fibres of the fabric and seal its pores without filling the superficial interstices, as shown in Fig. III. 50 In the latter case, the fabric is left with a

roughened or matted surface which will reflect light from head-lights even better than a smooth surface, and thus make the marker more conspicuous at night. In either case, this coating may be colored or pigmented to 55 contrast with the color of the pavements on which it is used,—i. e., generally colored white. When both sides of the fabric are coated, it may be found convenient to apply the coating by running the fabric through a 60 bath of the latter.

For bituminous cements, especially, cellulose ester lacquers are very suitable as coatings. They may either be used plain, or may be colored with any suitable pigments. 65

Having thus described my invention, I claim:

1. A pavement marking of fabric adapted to be cemented in place, cement-proofed with a coating that covers its fibres without completely filling their interstices, and thus having a roughened light-reflecting surface. 70

2. A pavement marking of woven fabric treated with a coating covering the threads without completely filling the interstices between the threads, and thus having a roughened light-reflecting surface. 75

In testimony whereof, I have hereunto signed my name at Rahway, N. J., this twenty-fifth day of March, 1927.

JOHN STROTHER MILLER, JR.
